(57) **CLAIM**

The ornamental design for a duffle with integral storage shroud, as shown and described.

DESCRIPTION

FIG. 1 is a perspective view of a storage shroud of the claimed design.

FIG. 2 is a front view thereof.

FIG. 3 is a top view thereof.

FIG. 4 is a bottom view thereof.

FIG. 5 is a left side view thereof.

FIG. 6 is a rear side view thereof.

FIG. 7 is a right side view thereof.

FIG. 8 is an enlarged perspective view of a duffle with integral storage shroud showing our new design.

FIG. 9 is a front view of FIG. 8.

FIG. 10 is a top view of FIG. 8.

FIG. 11 is a bottom view of FIG. 8.

FIG. 12 is a left side view of FIG. 8.

FIG. 13 is a rear view of FIG. 8; and,

FIG. 14 is a right side view of FIG. 8.

The broken-line showing of environmental structure is for illustrative purposes only and forms no part of the claimed design.
